(57) CLAIM

The ornamental design for a bottle, as shown and described.

DESCRIPTION

FIG. 1 is a perspective view of a bottle;
FIG. 2 is a second perspective view thereof;
FIG. 3 is a third perspective view thereof;
FIG. 4 is a rear elevation view thereof;
FIG. 5 is a right elevation view thereof;
FIG. 6 is a front elevation view thereof;
FIG. 7 is a left elevation view thereof;
FIG. 8 is top plan view thereof; and,
FIG. 9 is a bottom plan view thereof.
The broken lines indicate features of the bottle design that do not form part of the claimed design.

1 Claim, 8 Drawing Sheets
